INVENTOR
Richard Seggerman.
BY
Arthur C. Brown,
ATTORNEY

UNITED STATES PATENT OFFICE.

RICHARD SEGGERMAN, OF FAIRBURY, NEBRASKA.

CAN-STERILIZING APPARATUS.

Application filed June 13, 1921. Serial No. 477,077.

To all whom it may concern:

Be it known that I, RICHARD SEGGERMAN, a citizen of the United States, residing at Fairbury, in the county of Jefferson and State of Nebraska, have invented certain new and useful Improvements in Can-Sterilizing Apparatus; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to a can sterilizing apparatus and one of the objects of the invention is to provide an efficient, inexpensive sterilizer particularly adapted for sterilizing milk or cream cans.

20 Creameries and dairies usually have a number of receiving stations distributed over a relatively wide area and it is to these stations that the dairymen bring the milk and cream to be shipped to the creamery or dairy.

25 The farmer or dairyman who supplies the milk or cream to the stations in the outlying districts usually insists upon retaining control of his own milk cans for fear they 30 may be lost or for other reasons. Therefore, it is desirable that when the milk or cream is dumped from the farmer's can that such can be sterilized preparatory to sending it back to its owner.

35 It is, therefore, the purpose of my invention to provide a sterilizer, the cost of which will not be prohibitive for small stations and which will efficiently sterilize the can, wash it and dry it so that it can be returned 40 in a sanitary condition.

The novel construction of the invention will be apparent by reference to the following description in connection with the accompanying drawings, in which—

45 Fig. 1 is a perspective view of a sterilizing washer constructed in accordance with my invention, and

Fig. 2 is a vertical, longitudinal, sectional view through the sterilizer and washer.

50 1 designates a supporting frame or stand within which is mounted a plurality of burners 2, which may be supplied with fuel oil from a suitable source as, for example, the tank or reservoir 3. The source of heat supply, however, is immaterial.

Supported upon the frame or table 1 is a steam generator 4 having an inlet 5 at the top and provided with a pressure gauge 6 whereby the pressure within the tank may be observed. The upper portion of the steam generator tank 4 constitutes a steam dome, as at 7, from which leads a steam pipe 8, discharging through a nozzle 9, concentric with the conical, hopper-shaped portion 10 of a can-supporting table 11, one end 65 of which may be supported by the tank 4 and the other by a wash tank 12, supported on the standards 13.

The pipe 8 is provided with a right angular extension 14, which is the connector between the nozzle 9 and the pipe 8 and the connector is provided with a valve 15 by which the flow of steam may be admitted to and cut off from the nozzle 9.

There is another pipe 16 leading from the pipe 8 below the pipe 14 and this pipe is termed a condensate pipe, provided with a valve 17 and discharging into the tank 12 to warm the water therein. It is desirable that the pipe 16 be on a lower plane than the pipe 14 so that any condensed steam will accumulate therein, ready to flow into the tank 12 when the valve is opened and not discharge through the nozzle 19, as will be apparent by reference to Fig. 1.

75 The tank 12 has a discharge nozzle 18 by means of which it may be drained.

A hot air pipe or conduit having a lateral, intermediate portion 19, a depending inlet end 20 and an upstanding outlet end 21, is carried by the frame 1 and the intermediate portion 19 lies over the burners 2 so that the air within the portion 19 may be heated, causing a draft through the inlet 22 so that there will be a circulation of air up through the discharge end 23 of the heater pipe.

80 There are spacing cleats 24 and 25 on the table 11 and on opposite sides of the discharge 23 of the heater pipe, as will be apparent by reference to Fig. 1.

85 When the farmer or dairyman brings the milk to the receiving station, the can may be tilted on the table 11 to discharge into the open or funnel-shaped portion 10, it being understood that there will be another can 26 beneath the funnel or hopper to receive the discharged contents of the first named can, shown in dotted lines in Fig. 2 as 27.

100 Then the operator will open the valve 11'

15 to admit steam from the nozzle 19 into the can 27 so as to dislodge any adhering particles of butterfat so that these may drop into the hopper and into the can 26. The 5 can may then be swung over the end of the table 11 into the washing vat or tank 12, the temperature of the water in the vat being maintained by the condensate discharging from pipe 16 but in the event that 10 it is necessary to bring the temperature higher than possible by the condensate, live steam may be admitted from the pipe 8. The can is thoroughly washed in the vat and then again placed over the nozzle 9 15 to sterilize the interior thereof. It is then placed over the discharge end 23 of the drier, the end of the can resting upon the cleats 24 and 25 so that fresh hot air may be admitted into the can, from the heater 20 pipe and the damp air exhausted between the cleats 24 and 25 and the table 11. The heated air entering the can from the nozzle 23 will dry the interior thereof and restore it to its original condition, ready to again 25 be used.

By using my improved form of drier it will be readily seen that only pure hot air is used in drying the can and that no fumes from the burner can enter the drier 30 pipe to contaminate the air and cause a foul odor in the can after the process is completed.

Of course, the initial sterilization may take place from the nozzle 9 but the hot 35 dry air will also tend to render the interior of the can sterile.

From the foregoing it will be apparent that a device constructed in accordance with my invention will be inexpensive, durable and efficient in cleaning and sterilizing 40 vessels, such as milk cans and the like.

What I claim and desire to secure by Letters-Patent is:

1. A device of the class described comprising a wash tank and a steam generator 45 spaced one from the other, a table bridging the gap between them and supported by the wash tank and steam generator, a funnel-shaped can-receiving member in the table, a steam nozzle extending through 50 the funnel-shaped member and connected to the steam generator, and means for controlling the steam admitted to the steam nozzle.

2. A device of the class described comprising a wash tank and a steam generator spaced one from the other, a table bridging the gap between them and supported by the wash tank and steam generator, a funnel-shaped can-receiving member in the 55 table, a steam nozzle extending through the funnel-shaped member and connected to the steam generator, means for controlling the steam admitted to the steam nozzle, and a condensate pipe communicating with the 60 source of steam supply and discharging into 65 the wash tank.

3. In a device of the class described, a table having a funnel-shaped recess to receive the inverted ends of milk cans, a steam 70 jet nozzle concentric with and extending through the funnel-shaped recess, a wash tank adjacent the funnel-shaped recess, a steam supply pipe for said nozzle, a condensate pipe located beneath said nozzle 75 and adapted to receive the condensation from said steam pipe and said nozzle, and a valve for discharging said condensate pipe into said wash tank.

In testimony whereof I affix my signature. 80

RICHARD SEGGERMAN.
